UNITED STATES PATENT OFFICE.

WILLIAM A. HOLLAND, OF LONDON, OHIO.

FENCEPOST.

1,373,560.

Specification of Letters Patent.

Patented Apr. 5, 1921.

Application filed June 22, 1917. Serial No. 176,265.

To all whom it may concern:

Be it known that I, WILLIAM A. HOLLAND, a citizen of the United States, residing at London, in the county of Madison and 5 State of Ohio, have invented certain new and useful Improvements in Fenceposts, of which the following is a specification.

This invention relates to fence posts and is particularly directed to an improved type 10 of base for posts whereby the post may be erected in position without necessarily digging a hole in the ground and also whereby the post will be held in substantially a rigid position when once set in position.

15 In this connection, the main object of my invention resides in a stabilizer structure whereby the post is held in a substantially rigid position. This main stabilizer structure is also supplemented, if desired, by a 20 supplemental stabilizer structure which is slidably mounted upon the main rod forming the base unit and is driven into position after the base has been set.

The preferred embodiment of my invention 25 is shown in the accompanying sheet of drawings, in which similar characters of reference designate corresponding parts, and in which:

Figure 1 is a view in side elevation, a portion being broken out, of my improved type 30 of fence post base,

Fig. 2 is an edge view of the upper portion of the base, and,

Fig. 3 is a top plan view of the structure 35 shown in Figs. 1 and 2.

In these drawings, the base is shown as comprising a main rod 1, which carries a screw pointed end 2 at its bottom, which screw terminates at its upper end in a materially widened spiral shaped flight 3. The 40 screw 2 and flight 3 may be made one as desired, or the entire structure may be formed integrally upon the rod 1, the essence of this portion of the structure being 45 the fact that the screw 2 assists in drawing the post into the ground, it being supplemented in this action by means of the flight 3, which latter also serves as a stabilizer to prevent the post from leaning one 50 way or another. The earth upon the top and bottom sides of this flight act to prevent this action and likewise this flight prevents the ready removal of the base by a direct upward pull. At its upper end, the rod 1

carries a supplemental stabilizer in the form 55 of a plate 4 having a pointed end 5 and being medially formed to fit the rod 1. As is shown in Figs. 1 and 2, this plate is stamped medially to semi-circular shape at the portions indicated by the numeral 6, 60 while at the points indicated by the numeral 7, the material of this plate is stamped in the opposite direction but to a shape to substantially fit the rod 1. In this manner, the plate may be slid into position over the 65 upper end of the rod and may be driven into the ground after the base has been sunk the desired depth. In order to clamp the plate in position after it has been thus forced into the ground, I have provided a 70 supplemental clamp 8, which is provided with pierced ears to coöperate with the bolt and nut structures shown at 9 in the well known manner. The upper end of the rod 1 terminates in a squared end 10 provided 75 with a series of apertures 11 upon which end the fence post itself may be secured. It will be understood that the particular shape of the upper end of this rod is not essential to the present invention, as naturally this end 80 would be shaped to fit the particular type of post desired to be used.

From the foregoing description, it will be apparent that I have provided a base for a post which may be readily placed in position 85 in the ground due to the screw pointed end 2 and the materially enlarged flight 3. This flight 3 serves additionally as a stabilizer to prevent the post leaning one way or another and in addition serves as a guard to prevent 90 the ready removal of the base by a direct pull. Further, the supplemental stabilizer is resorted to and is placed in position by driving it into the ground after the base has been set. After this, it may be clamped in 95 position by means of the clamp plate 8 if desired, although this latter is not absolutely necessary.

What I claim, is:

1. In a fence post adapted to be driven 100 into the ground, a stabilizer slidably mounted thereon comprising a plate having its center portion concaved to present a longitudinal post engaging groove, and a supplemental clamp structure in coöperation with 105 said groove to complete the attachment of the stabilizer to the post.
2. In a fence post adapted to be driven

into the ground, a stabilizer mounted thereon comprising a plate tapered at its bottom end and having a portion of its center concaved to form a post engaging groove and 5 another portion concaved oppositely to also form a post engaging groove and a supplemental clamp structure coöperating with one of said grooves to rigidly secure said

stabilizer to said post after both are driven into the ground.

10 In testimony whereof I affix my signature in presence of two witnesses.

WILLIAM A. HOLLAND.
